UNITED STATES PATENT OFFICE

ALBERT BODMER, OF WATTWIL, SWITZERLAND, ASSIGNOR TO HEBERLEIN & CO. A. G.,
OF WATTWIL, SWITZERLAND, A CORPORATION OF SWITZERLAND

PROCESS FOR ORNAMENTING TEXTILE MATERIALS AND PRODUCTS THEREFROM

No Drawing. Application filed September 14, 1929, Serial No. 392,730, and in Germany July 10, 1929.

This invention relates to a process for ornamenting textile materials and particularly to a process for production of brocade effects on woven materials; and to the materials resulting from such processes.

One of the objects of the invention is to provide a simple efficient process of the kind described for producing the desired effects using relatively inexpensive starting materials and requiring only simple apparatus for carrying out the process. Another object of the invention is to produce a product simulating the brocade but at a much lower cost than brocades can be produced.

It is known that patterns can be produced upon fabrics as in goffering by exerting local pressure thereon. Such decorative portions are distinguished from the other portions of the fabric by hollow raised portions which appear in relief.

It has now been found that a hitherto unknown improvement in such effects obtained by pressing may be produced by special procedures. For this purpose one produces a fabric in which yarns are present which have previously been treated with a preparation providing a coating of binding material and pigment. If such material is then locally pressed by a suitable pressing means, the prepared yarns because of their pigment- and binder-contents, fill the interstices between the adjacent threads, so that on the particular pressed portions a closed surface results which differs markedly from the rest of the material.

The preparation of the yarns to be used for this purpose consists in applying to the material suitable pigments by means of a binding material. As a binding means glue, rubber, lacquers of various composition, for example, of nitro-cellulose or acetyl cellulose can be used. As pigments, mineral and earth colors, lake colors and metal powders may be employed. The latter have shown themselves particularly effective in use. Cellulose lacquers have advantage over the ordinary binders because of their greater stability.

The prepared yarns can be included in the surface of textile materials in any desired

manner. For example, they may be included in woven fabrics, embroidery, knitted goods, ribbons, etc., and particularly in combination with unprepared yarns made up of fibers as desired. Weavings of this kind for which the present invention is particularly devised may consist, for example, in the direction of the warp of ordinary natural or artificial fibers, in the other direction (that is, the filler), of prepared fibers or vice versa. Or the fabric may contain in one or the other or in both directions alternatively both the prepared and unprepared yarns, whereby the yarns singly, in pairs or in multiple may be arranged along side one another. One may also produce structures which contain only yarns prepared in the same manner or yarns prepared in different manners. The yarns to be prepared may consist of chosen, natural or artificial fibers. The pressure effects are produced in the usual manner by pressing with plates or roller-like forms. According to the kind of yarns employed and the effect desired, the pressing may be carried out with greater or less pressure. In many cases it is advantageous to work with heated pressing devices whereby the temperature must be adjusted to the material employed.

Examples of procedure

1. A fabric is woven whose warp contains prepared cotton yarn. The preparation of this cotton yarn consists in coating it with alizarine lake with collodion as the binding means. A design is pressed on the prepared fabric by means of a plate press.

2. A fabric is prepared in which the warp consists of a hard twisted artificial silk and prepared yarns are woven in as a filler. The yarns are previously provided with a coating of a mixture of dissolved acetyl cellulose and so-called gold bronze powder. A pattern is pressed in the prepared fabric by passing it through a goffer calender by means of a goffer roll, heated to approximately 130° C.

The process described is a simple efficient one which may be carried out by inexpensive apparatus and employing inexpensive material. The effects produced are pleasing and the cost of the finished material is of course

much lower than that of the usual brocade.

Thus while I have described my improvements in detail and with respect to certain preferred forms, I do not desire to be limited to such details or forms since, as will be noticed by those skilled in the art, after understanding my invention many changes and modifications may be made and the invention embodied in widely different forms without departing from the spirit and scope thereof in its broader aspects, and I desire to cover all modifications, forms and improvements coming within the scope of any one or more of the appended claims.

Having thus described my invention, what I claim as new and desire to secure by Letters Patent is:—

1. A process for ornamenting textile material which comprises taking a woven fabric having interstices between the threads thereof and containing a substance capable of filling interstices thereof, applying a patterning device to said fabric and causing said substance to fill interstices in portions of the fabric corresponding to the pattern while leaving other interstices open.

2. A process for ornamenting textile material which comprises taking a woven fabric having interstices between the threads thereof and containing some threads having thereon a substance capable of filling interstices of said fabric, applying a patterning device to said fabric and causing the substance to fill interstices in portions of the fabric corresponding to the pattern while leaving other interstices open.

3. A process for ornamenting textile material which comprises coating threads of the material with a colored binder, said binder being capable of filling interstices in fabric woven from said thread, weaving said thread into a fabric, applying a patterning device under pressure to the fabric and causing the binder to fill interstices in the fabric thereby producing a closed shiny surface where the design is impressed on a background of fabric with its meshes or interstices still open.

4. A process for ornamenting woven fabric including the usual sets of warp and filler threads which comprises coating the warp threads with a pigmented binder, said binder being capable of filling interstices in fabric woven with said warp, weaving said fabric including said warp, goffering the fabric and causing the binder to fill interstices in the fabric thereby producing a closed shiny surface where the design is impressed on a background of fabric with its meshes or interstices still open.

5. A woven textile material including coated threads forming a portion having open interstices and another portion having its interstices filled by said binder in a desired pattern.

6. A woven textile material comprising

coated threads forming a portion having open interstices and another portion having a colored binder pressed thereinto to fill its interstices to form a desired pattern.

7. A woven textile material having warp and filler threads, one set of threads being coated with a colored binder capable of filling interstices in the woven fabric when pressed, said material having a portion containing interstices between the threads and another portion with said binder pressed into the interstices and filling the same to produce a closed shiny surface in a desired pattern.

8. A woven textile material having warp and filler threads, said warp threads being coated with a colored binder capable of filling interstices in the woven fabric when pressed, said material having a portion containing interstices between the threads and another portion goffered thereon to fill the interstices in a desired pattern.

In testimony whereof I have signed my name to this specification.

ALBERT BODMER.
